UNITED STATES PATENT OFFICE.

WILLIAM W. RIDGELY, OF SYRACUSE, NEW YORK, ASSIGNOR, BY MESNE ASSIGNMENTS, TO RIDGELY HEATER COMPANY, OF SCRANTON, PENNSYLVANIA, A CORPORATION OF NEW JERSEY.

HEATER.

Application filed July 15, 1925. Serial No. 43,799.

This invention relates to heaters, but more particularly to supplemental fire boxes and supporting means therefor of the class set forth in my pending application #757,467, filed Dec. 22, 1924, in which the main object is to support the fuel in such manner that fresh air for supporting combustion may come in contact with the bottom, sides and top of the combustible fuel throughout the area thereof from bottom to top.

Another object is to construct the supplemental sides of the box in sections of sufficiently small size to permit them to be easily and quickly installed in place ready for use through the fuel or ash opening of the heater.

In most of the hot air furnaces, the hot water and steam boilers and house heaters in general using solid fuels, the ash box and overlying grates extend forwardly and rearwardly in more or less straight lines so that the sections of the grate are arranged within a rectilinear area parallel with the sides of the ash pit while in many furnaces the combustion chamber is substantially circular, and one of the specific objects of the present invention is to construct the sections of the supplemental fire box in such manner that when assembled the lower portion thereof will be substantially rectangular and the upper portion circular so that the circular portions of the sections gradually merge into flat portions at the bottom.

Another object is to provide the lower ends of the supplemental sections and supporting frame therefor with cooperative locking means whereby when the frame is properly installed the sections may be placed thereon and held against lateral or circumferential movement without any other fastening means.

Another specific object is to flare the upper ends of the sections outwardly to enable them to rest against the inner walls of the combustion chamber for additionally holding them against radial displacement.

A further object is to provide a supporting frame for the grate bars and supplemental sections capable of being easily and quickly installed in the place of the grate-supporting frame commonly used in many furnaces of standard makes.

Other objects and uses relating to specific

parts of the apparatus will be brought out in the following description.

In the drawings:

Figure 1 is a top plan of the detached supplemental fire box and its supporting frame and grate bars in their assembled relation as used in a circular combustion chamber.

Figure 2 is a vertical sectional view of the apparatus shown in Figure 1 and adjacent portions of the fire box and ash pit taken in the plane of line 2—2, Figure 1.

Figure 3 is a horizontal sectional view taken in the plane of line 3—3, Figure 2.

Figures 4, 5, and 6 are detail sectional views taken in the planes of lines 4—4, 5—5 and 6—6, respectively, Figure 3, except portions of the front grate supporting bar are shown in elevation in Figure 4 and one of the grate bars and adjacent portion of the connecting link are shown in elevation in Figure 5.

As illustrated, the heater comprises an ash box or base section —A— and a circular fire pot —B— within which is mounted a supplemental frame —1— carrying a supplemental fire box —2— and a plurality of grate bars —3—.

The ash box —A— is elongated from front to rear and is provided with parallel sides and a substantially semi-circular rear end substantially concentric with the lower end of the fire box —B— which rests upon an annular flange —a— on the top of the ash box and around a circular opening —a'— therein for establishing communication between the interior of the fire box and ash pit.

The front end of the ash box is disposed in a plane at substantially right angles to the sides thereof and is provided with a relatively large opening —a''— for clean-out and draft purposes and also for receiving the front ends of the grate bars —3—.

The rear end of the ash box is preferably closed and provided with a series of parallel sockets —a'''— arranged in transversely spaced relation but in the same horizontal plane with their open ends facing forwardly, the outermost sockets being arranged at equal distances from the longitudinal center of the ash box for a purpose presently described.

A pair of parallel horizontal bars —4—

are removably supported at their rear ends in the outermost sockets —a'''— to extend forwardly therefrom within the upper portion of the ash box —A— and are supported at their front ends by a transverse bar —5— which is secured by bolts —6— or equivalent fastening means to the underside of the top of the ash box —A— and is provided in its lower side with recesses —7— for receiving the front ends of the bars.

A pair of plates —8— are each secured by bolts —9— to the cross bar —5— across the lower open sides of the recesses —7— for holding the side bars —4— in said recesses and in fixed relation to the cross bar —5—.

The height of the recesses —7— is slightly less than the diameter of the bars —4— to permit the adjacent ends of the bars to be tightly clamped between the plates —8— and upper walls of the recesses when the bolts —9— are drawn up tightly thereby holding the bars against axial displacement when adjusted for use.

The supplemental frame —1— is substantially rectangular or, in this particular instance square, in top plan and is supported in a horizontal plane directly upon the upper faces of the bars —4— and centrally within the central opening —a'— in the top of the ash box and for this purpose its opposite sides are provided with laterally projecting lugs —10— near the corners thereof as shown more clearly in Figures 3 and 6.

This supplemental frame —1— is of less width than the opening —a''— in the front of the ash box to permit it to be placed in operative position through said opening and when properly positioned with the lugs —10— resting on the upper faces of the bars —4— its center will be substantially coaxial with the axis of the circular fire pot —B— and supplemental fire pot —2—.

The area of the supplemental frame —1— is considerably less than the area of the opening —a'— in the top of the ash box thereby leaving considerable space between the marginal edge of said frame and walls of the ash box for the passage of air therethrough.

As previously stated the supplemental frame is rectangular or in this instance square and the opening therethrough is also square and determines the fuel area exposed to the grates.

The intermediate portions of the front and rear ends of the frame —1— are provided with flanges —11— and —12— extending downwardly between the bars —4— for receiving and supporting the grate bars —3— in a substantially horizontal plane, the rear flanges —12— being provided with journal openings —13— for receiving the rear ends of the grate bars —3— while the front flanges —11— are provided with recesses —13'— open at the bottom to permit the

grate bars to be placed from the underside therein and seated against the top walls of the recesses —13— where they are held in place by a separate cross plate —14—.

This cross plate —14— is secured by bolts —15— to the front face of the front flange —11— and is provided with recesses —16— open at the top for receiving the adjacent portions of the grate bars —3— as the bar —14— is placed in operative position from the bottom upward and when secured in place serves to hold the front ends of the grate bars in the recesses —13'— with sufficient play to permit the grate bars to be easily rotated or rocked upon their axes for removing the ashes from the grates.

The portions of the grate bars within the frame —1— are provided with triangular flanges —16—, those of each bar being arranged in sequence from front to rear and are of equal size and are normally positioned with one of their sides facing upwardly to support the solid fuel which may be placed in the supplemental fire box —2—.

The grate bar shafts —3— extend forwardly some distance beyond the horizontal bar —5— and are provided with enlarged extremities —17— having triangular sockets —18— either of which is adapted to receive a correspondingly shaped hand crank for oscillating or shaking the grates to remove the ashes from the burned fuel.

The intermediate portion of the cross bars —5— is provided with recesses —19— open at the bottom for receiving the adjacent portions of the grate bars —3— which are held in said recesses by an underlying plate —20— and suitable clamping bolts —21— securing said plate to the underside of the cross bar —5— independently of the plates —8— previously described.

Each of the four sides of the upper portion of the supplemental frame —1— is provided along its inner edge with a pair of upwardly projecting lugs —22— in longitudinally spaced relation equal distances from the center thereof while the outer edges of each side are provided with a centrally disposed upstanding lug —23— said lugs being disposed in different transversely spaced vertical planes for receiving and supporting the lower ends of the corresponding sides of the supplemental fire pot —2—, presently described.

The portions of the grate bars —3— between the cross bar —5— and heads —17— are provided with triangular flanges —24— of substantially the same form and size as the flanges —16— all of said flanges being arranged with one of their angles or apexes at the bottom and consequently one of their flat sides at the top as previously explained.

The lower apexes of the flanges —24— are pivotally connected by bolts —25— to and between the opposite walls of a channel bar

—24'— for transmitting rocking motion from one grate bar to the other when either is shaken.

The object in connecting the lower apexes 5 of the flanges —24— in the groove channel bar as —24— is to utilize the bottom of the channel bar to cooperate with the edges of the flanges for limiting the rocking movement of the grate bars and preventing accidental dumping of the fuel.

The supplemental fire box —2— as illustrated has a circular upper portion and a square or rectangular lower portion corresponding to the size and shape of the supplemental frame —1— upon which it is adapted to rest, the lower ends of the circular portion being gradually merged with the straight sides of the lower portion without any abrupt breaks in the continuity of 20 the inner surface of the supplemental fire pot from top to bottom.

The supplemental fire pot —2— as a whole flares outwardly and upwardly from its lower end to the upper end which latter is 25 of substantially the same diameter as the interior diameter of the adjacent portion of the fire pot —B— so as to rest against the same and thereby to assist in holding the supplemental fire pot and its supporting 30 frame —1— against lateral movement relatively to the ash box —A— and main pot —B—.

It will be understood from the foregoing description that the supplemental fire box 35 is made somewhat in the form of an inverted bell or an inverted truncated cone except that the smaller end is square or rectangular and by flaring the sides of this fire box upwardly in the manner described 40 a relatively small portion of the marginal edge of the upper end is engaged with the outer fire pot —B— while the remaining portions are in spaced relation thereto to form a supplemental air and combustion 45 chamber —26— between the two fire pots and extending nearly the entire length of the supplemental fire pot except the small area of contact with the outer fire pot —B—.

The supplemental fire box —2— is preferably divided vertically into four equal sections in planes passing diagonally through the corners of the frame —1— and axis of both fire pots, one section for each side of the supplemental frame —1—.

The lower edge of each section is therefore straight and of substantially the same length as the corresponding side of the supplemental frame —1— and is provided with longitudinally spaced recesses —27— for receiving the lugs —22— which serve to hold the lower ends of the section against inward and circumferential displacement and affords a simple means for properly positioning the sections in place upon the supplemental frame without other

fastening means, while the shoulders —23— engage the outer faces of the lower ends of the sections to hold the latter against outward displacement without other retaining means.

The upper ends of the several sections have rather an abrupt outward flare at —28— to bring the extreme upper edges thereof against the adjacent portions of the outer fire pot —B— and at the same time 75 to space the remaining portions of the supplemental fire pot away from the outer fire pot to form the chamber —26—.

The flattened or straight lower portions forming the lower ends of four sides of the supplemental fire pot are relatively short vertically so that the remaining portions above the flattened portions are circular and constitute the major portion thereof.

It is, therefore, evident that each section 85 of the supplemental fire pot has a substantially straight or flattened lower end and a circular upper portion and in order to produce a gradual merging of the flattened with the circular portion the line of merger as —a—, Figure 2 would be in form of an arc of a circle of greatest height at the center and gradually reducing in height to practically zero in the ends, the result being that the opposite edges of each section aside 90 from the abrupt flare at —28— is substantially straight but inclined upwardly and outwardly while the degree of inclination from a vertical of the flattened portion of each section midway between its edges would 100 be greater, as at —29—, than the circular portions.

Under these conditions the main body of the fuel in the upper circular portion of the fire box —2— will feed downwardly more 105 abruptly than that which rests upon the lower flattened sides which tends to retard the abrupt downward feed of the adjacent portions of the fuel and to assist in concentrating the fuel within the relatively smaller area of the supplemental frame —1— and upon the upper faces of the adjacent portions of the grates —16—.

One of the objects of making the supplemental fire pot in sections of similar size 115 and shape is to enable them to be cast from a single mold and a further object is to enable them to be made of sufficiently small size so that they may be installed in place upon the frame —1— through the fuel opening, but if the fuel opening is too small to permit the passage of the sections therethrough they may be inserted through the ash door opening into the ash box, then temporarily supported in any suitable manner within the fire pot —B— until the supplemental frame —1— and grates —3— are 120 installed ready to receive them in which case they may be properly placed upon the frame —1— either through the opening to 125 130 135

the ash box or through the fuel opening by simply bringing the recesses —27— of each section into registration with the corresponding lugs —22— and within the 5 outer flange —23—.

The several sections of the supplemental fire box are provided with one or more, in this instance three, horizontal rows of vertically elongated openings or slots —30— 10 therethrough for connecting the supplemental chamber —26— with the supplemental combustion chamber in the fire pot —2— and thereby permitting the passage of air from the ash pit upwardly into the chamber —26— and thence through the passages —30— to the fuel for stimulating combustion of said fuel at all levels in the supplemental fire pot in addition to the supply of air through the grates and opening in the 20 supplemental frame —1—.

This means for supplying fresh air to the fuel at all levels from top to the bottom of the supplemental fire pot causes a more complete combustion and incineration of all 25 of the fuel thereby producing a more intense heat with a given quantity of coal and at the same time burning the gases and reducing the smoke content of the escaping gases to a minimum, resulting in a large saving of 30 fuel and a relatively small amount of fine ash residue.

If at any time it should become necessary to remove any one or both of the grates it is simply necessary to remove the plates 35 —14— and —20— thus permitting the front ends of the grates to drop down out of the recesses —13'— and —19— whereupon the 40 grate bars may be withdrawn from the respective bearings —13— in the flanges —12— and thence outwardly through the opening in the front end of the ash box.

After the grates have been removed in the manner described, the supplemental frame —1— may also be removed by simply 45 removing the plates —8— from the underside of the cross bar —5— whereupon the bars —4— may be withdrawn from the sockets —a''— through the open front end 50 of the ash box to allow the frame —1— to drop downwardly into the ash box from which it may be removed through the front end thereof.

This removal of the frame —1— releases 55 the sections of the supplemental fire pot and permits them to be readily disengaged one

from the other and removed either from the fuel door or dropped down to the ash box and removed therefrom.

What I claim is:

1. In a heater of the character described, 60 an ash box having an opening in its top, a fire pot seated on the top of the ash box around the opening, socketed bearings on the rear end of the ash box, a cross bar supported from the top of the ash box in front 65 of said opening and provided with recesses, horizontal bars having their rear ends mounted in the socketed bearings and their front ends supported in the recesses of said cross bar, a frame resting upon the horizontal bars in spaced relation to the walls of said opening, a supplemental fire pot having its lower end seated on the upper face of the frame and its upper end engaged with the walls of the first-named fire pot and its 70 remaining portions in spaced relation to said walls to form an intervening air chamber communicating with said opening, said supplemental fire pot being perforated throughout the greater portion of its height to permit the passage of air from said chamber to the fuel at different levels.

2. In a heater of the character described, 75 an ash box, a pair of parallel horizontal bars adapted to be supported in spaced relation in the upper portion of the ash box, a frame resting upon the upper faces of the bars and slidably adjustable thereon, a supplemental fire pot flaring upwardly from bottom to top 80 and having its lower end resting upon the upper face of the frame, said fire pot being perforated throughout the greater portion of its area.

3. In a heater of the character described, 95 an ash box, a pair of parallel horizontal bars adapted to be supported in spaced relation in the upper portion of the ash box, a frame resting upon the upper faces of the bars and slidably adjustable thereon, a supplemental fire pot flaring upwardly from 100 bottom to top and having its lower end resting upon the upper face of the frame, said fire pot being perforated throughout the greater portion of its area, and grate bars journaled on the frame between and parallel 105 with the first-named bars.

In witness whereof I have hereunto set my hand this 11th day of May, 1925.

WILLIAM W. RIDGELY.
